UNITED STATES PATENT OFFICE.

RALPH L. LEE, OF DAYTON, OHIO, ASSIGNOR TO DELCO-LIGHT COMPANY, OF DAYTON, OHIO, A CORPORATION OF DELAWARE.

DOMESTIC APPLIANCE.

Application filed November 15, 1923. Serial No. 675,016.

To all whom it may concern:

Be it known that I, RALPH L. LEE, a citizen of the United States of America, residing at Dayton, county of Montgomery and 5 State of Ohio, have invented certain new and useful Improvements in Domestic Appliances, of which the following is a full, clear, and exact description.

This invention relates to wringers, and 10 more particularly to clothes wringers, and has for its object to prevent the clothes wrapping around one of the wringer rolls.

Further objects and advantages of the present invention will be apparent from the 15 following description, reference being had to the accompanying drawing wherein a preferred embodiment of one form of the present invention is clearly shown.

In the drawings:

20 Fig. 1 is a view in elevation of a clothes wringer embodying the present invention.

Fig. 2 is a sectional view taken on the line 2—2 of Fig. 1.

25 Referring to the drawings, a U-shaped wringer frame 20 is secured to a mounting bracket 21 in any suitable manner, and supports bearing blocks 22 and 23 for shaft 24 of lower wringer roll 25, and bearing blocks 26 and 27 for shaft 28 of upper wringer roll 29. Lower wringer roll 25 may be operated in any suitable manner, as by power driven means or by securing a crank to shaft 24. Shaft 24 carries a gear 30 which meshes with a gear 31 carried by shaft 28 of upper 30 wringer roll 29, whereby on operation of roll 25, roll 29 will also be operated. A leaf spring 35 is supported at its opposite ends by bearing blocks 26 and 27. A screw 36 having threaded engagement with wringer 35 frame 20 bears upon the central portion of spring 35 and may be adjusted by the wheel 37 to vary the tension of spring 35 and thereby vary the pressure between the wringer rolls 25 and 29. A drain board 40 is pivotally mounted on the wringer frame 20 below the lower wringer roll 25 by pins 41 and 42. Drain board 40 carries at its opposite ends rollers 43 and 44 for receiving an endless conveyor belt 45 which is adapted to be 45 propelled by contact with wringer rolls 25 and 29, passing between said rolls and be-

tween lower wringer roll 25 and drain board 40.

The means for preventing clothes wrapping around one of the wringer rolls comprises metal rings 50 which encircle roll 29 and fit in spaced annular grooves 51 provided in upper wringer roll 29. The diameter of these rings 50 is greater than the outside diameter of roll 29, extending above the 55 upper edge of roll 29, as viewed in Fig. 1 and being received by spaced slots 53 which are in alignment with the spaced grooves 51 in roller 29. The slots 53 serve as guides for rings 50 and for maintaining them in a vertical position as shown in Fig. 1. It will be apparent that when pressure is applied to the wringer rolls, rings 50 will be pinched between said rolls and are movable with the 60 clothes passing through said rolls.

When clothes are placed on the conveyor belt 45 and carried between the wringer rolls 25 and 29, for wringing, the rings 50 by their 65 rotative movement tend to keep the clothes pushed down toward the conveyor belt 45 and overcome any tendency of the clothes to stick to the upper wringer roll 29 and wrap around said roll.

While the form of embodiment of the invention as herein disclosed, constitutes a preferred form, it is to be understood that other forms might be adopted, all coming within the scope of the claims which follow.

What is claimed is as follows:

1. In a wringer, the combination with a 85 pair of wringer rolls for engaging articles to be wrung, and a ring encircling one of the rolls and movable with the articles for preventing the articles wrapping around said roll.

2. In a wringer, the combination with a pair of wringer rolls one of which is provided with a plurality of relatively narrow-spaced annular grooves; of a plurality of relatively narrow rings each encircling the 95 grooved roller and each received by one of the grooves, said rings being greater in diameter than the roll encircled by them and movable with the articles being wrung during the operation of the wringer in order to 100 prevent said articles wrapping around one of the rolls.

3. In a wringer, the combination with a pair of rolls for engaging articles to be wrung, one of said rolls being provided with spaced annular grooves; of a supporting frame having grooves in alignment with the grooves in the grooved roll; and rings of greater diameter than that of the grooved
- roll received by the grooves in said roll and in the supporting frame and movable with the articles for preventing articles sticking to the grooved roll.

In testimony whereof I hereto affix my signature.

RALPH L. LEE.
